UNITED STATES PATENT OFFICE.

THOMAS A. LEWIS AND ARTHUR L. DUNHAM, OF NEW YORK, N. Y., ASSIGNEES TO
BRANFORD ELECTRIC COMPANY, A CORPORATION OF NEW YORK.

ELECTRIC HEATER.

Application filed March 20, 1920. Serial No. 367,538.

To all whom it may concern:

Be it known that we, THOMAS A. LEWIS and ARTHUR L. DUNHAM, citizens of the United States, and residents of New York city, New York, the former of New York County and the latter of Richmond County, in said city and State, have invented a new and useful Improvement in Electric Heaters, of which the following is a specification.

10 Our invention relates to electric heaters. It has for its object to provide a new and improved heating element for electric heaters, capable of withstanding high heat, cheap and easy of construction, easily removable and replaceable, efficient and durable in operation, and one capable of being used with safety where inflammable gases are present. It consists of the new and improved electric heater hereinafter described.

20 In electrical heating devices heretofore employed in practical use the heating element is exposed to the atmosphere, and accordingly is liable to corrosion and oxidation, especially where high heat is employed, and it is dangerous to use where inflammable gases are apt to be present. The liability to oxidation limits the range of temperature that may practically be employed without rapid destruction of the heating element, necessitating the keeping of the said element at a lower temperature than otherwise might be desired, and of course decreasing the efficiency. Moreover, the removal of the heating element in such devices requires more work and skill than is possessed by most users of such devices.

Our invention overcomes all these difficulties. It provides a device that can safely be used anywhere; that can be used at extremely high temperatures without appreciably affecting its durability, that is simple in construction and operation, and in which the heating element can be removed and replaced by anyone.

45 In the drawings accompanying this specification we have shown our improvement as embodied in an ordinary reflector heater. It is to be understood, of course, that our invention can be employed in any suitable kind of electric heater. The drawings referred to include Fig. 1, a face view of our improved device in its preferred form and Fig. 2 a vertical cross-section of Fig. 1 on the lines 2—2 of Fig. 1 viewed as shown by 55 the arrows.

Referring now to the drawings, 1 is the stand of the reflector electric heater, 2 the upright, and 3 the reflector part. 4 and 5 constitute the usual wire guards for such a reflector. 6 is a sealed bulb preferably filled with an inert gas such as nitrogen. It is preferably made of a vitreous material of high heat resistance. 7 is the usual socket provided on its inner part with screw-threads as shown. 8 is the support for the bulb 6 made in any suitable way and secured to the bulb in any suitable manner. 9 is a core of insulating material such as porcelain or a refractorite composition, upon which is wound the heating element 10. 11 and 12 are wires leading from the ends of the heating element. These and the cable, are connected in the manner usual in lamp sockets. The support 8 of bulb 6 is screw-threaded on the outer side of its projecting part and is adapted to fit into the screw threads of socket 7 so that the bulb can be easily screwed in or removed like an ordinary incandescent lamp. The reflector 3 is provided with a ring 3^a connected by a spider 3^b to socket 7 to hold the socket in place in the reflector. This construction permits air to pass between the spokes of the spider.

We prefer to fill the bulb 6 with an inert gas such as nitrogen, as this helps to conduct the heat from the heating element, and renders the life of the heating element longer and permits it to be run at a very high temperature, thus increasing the efficiency of the heater without deterioration or destruction of the heating element. Where the bulb is made of glass we have found it advantageous to use frosted glass.

Any suitable material may be used for the heating element, but we prefer to use a metallic conductor of high heat and electrical resistance, as thereby our invention can be utilized to its fullest advantage. For example, we may employ any of the well known metals or metallic alloys possessing these properties. By our improvement very high heats can be maintained, and our device is accordingly useful for many purposes to which the ordinary electric heater is wholly unsuited. When a bulb is burned out it can easily be removed and replaced by anyone, and this ease of removal and replacement permits the heating element to be run at a much higher temperature than would otherwise be advisable.

We have found in practice that the use of the enclosing bulb causes a much more even distribution of the heat and minimizes to a considerable extent the deleterious effects of air currents around the heating element. Where the heating element is exposed to the atmosphere different parts of the heating element are apt to be heated to different intensities, and the air currents are irregular and uneven. Moreover the air comes directly into contact with the highly heated parts of the heating element, tending to increase the intensity of air currents and to cause them to vary so that much heat is carried upward and away from the reflector and is wasted. With our enclosing bulb the heat from the heating element as it passes through the gas in the bulb becomes more evenly distributed and more evenly equalized by the time it reaches the surface of the bulb, and, moreover, the heat at any particular point on the exterior surface of the bulb is lower than on the heating element. These differences tend to reduce the intensity of the air currents and cause them, and the heat rays, to be more evenly distributed, and more of them are carried to and discharged from the reflector. We have found in the use of heaters similar to the one illustrated in the drawings, that a great saving of heat is effected, and that the same results can be obtained with our improved device by the use of from a quarter to a third less wattage than is required in electric devices heretofore used. We have also found that a still greater saving is effected by the use of non-transparent glass for the bulb such as frosted or translucent or opaque or colored glass.

What we claim as new and desire to secure by Letters Patent, is:

1. The combination in a reflector type of heater, of a metallic electrical heating element of high electric and heat resistivity, an insulating and refractory support upon which the heating element is wound, and a sealed bulb enclosing the heating element.

2. The combination in a reflector type of heater, of a metallic electrical heating element of high electric and heat resistivity, an insulating and refractory support upon which the heating element is wound, a sealed

bulb mounted on said support and enclosing the heating element, the support, bulb and heating element being removable and replaceable as a unit in the heater. 55

3. The combination in a reflector type of heater, of a metallic electrical heating element of high electric and heat resistivity, an insulating and refractory support upon 60 which the heating element is wound, and a sealed non-transparent bulb enclosing the heating element.

4. The combination in a reflector type of heater, of a metallic electrical heating element of high electric and heat resistivity, an insulating and refractory support upon 65 which the heating element is wound, a sealed non-transparent bulb mounted on said support and enclosing the heating element, the support, bulb and heating element being removable and replaceable as a unit in the heater. 70

5. The combination in a reflector type of heater, of a metallic electrical heating element of high electric and heat resistivity, an insulating and refractory support upon 75 which the heating element is wound, and a sealed bulb containing an inert gas enclosing the heating element. 80

6. The combination in a reflector type of heater, of a metallic electrical heating element of high electric and heat resistivity, an insulating and refractory support upon 85 which the heating element is wound, a sealed bulb containing an inert gas mounted on said support and enclosing the heating element, the support, bulb and heating element being removable and replaceable as a unit in the heater. 90

7. The combination in a reflector type of heater, of a metallic electrical heating element of high electric and heat resistivity, an insulating and refractory support upon 95 which the heating element is wound, a sealed non-transparent bulb containing an inert gas mounted on said support and enclosing the heating element, the support, bulb and heating element being removable and replaceable as a unit in the heater. 100

In testimony whereof, we have signed our names to this specification.

THOMAS A. LEWIS.

ARTHUR L. DUNHAM.
